[57] CLAIM

The ornamental design for a solar powered barricade light, as shown and described.

DESCRIPTION

FIG. 1 is an upper, front perspective view of a solar powered barricade light showing my new design; FIG. 2 is a lower, rear perspective view thereof; FIG. 3 is a top plan view thereof on an enlarged scale; FIG. 4 is a front elevational view thereof on an enlarged scale;

FIG. 5 is a left side elevational view thereof on an enlarged scale;

FIG. 6 is a right side elevational view thereof on an enlarged scale;

FIG. 7 is a rear elevational view thereof on an enlarged scale; and,

FIG. 8 is a bottom plan view thereof on an enlarged scale.

FIG. 1.

FIG. 2.

FIG. 3.

FIG. 4.

FIG. 5.

FIG. 6.FIG. 7.FIG. 8.
